(57) **CLAIM**

The ornamental design for a tulip plant dripper as shown and described.

DESCRIPTION

FIG. 1 is a top perspective view of a tulip plant dripper showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof; and,

FIG. 9 is a perspective view thereof, showing the tulip plant dripper in a separated state. The broken lines in the drawings depict portions of the tulip plant dripper that form no part of the claimed design.
